(57) CLAIM

The ornamental design for a football flag, as shown and described.

DESCRIPTION

FIG. 1 is a perspective view of a football flag of the present invention shown in a position of use.

FIG. 2 is a rear view thereof.

FIG. 3 is a front view thereof.

FIG. 4 is a side view thereof; and,

FIG. 5 is a top plan view thereof.

The broken lines in the drawings represent stitching and form part of the claimed design.
